UNITED STATES PATENT OFFICE

JULES NICLAUSSE AND ALBERT NICLAUSSE, OF PARIS, FRANCE

STEAM GENERATOR

Application filed December 3, 1925, Serial No. 72,877, and in France October 9, 1925.

This invention has for its object a steam generator characterized by grouping around a common combustion chamber capable of being fed with powdered fuel, solid fuel or liquid fuel, a series of groups of tubular evaporating elements whose metal tubes form the walls of the said combustion chamber.

By this means the ordinary walls of refractory bricks of combustion chambers which 10 resist badly the high temperatures of direct radiation from the hearth and which are costly to maintain, are avoided.

As the walls of the combustion chambers are formed of vaporizing tubes thus exposed 15 to direct radiation from the hearth, the efficiency of the boiler is very high and moreover by reason of the intense absorption of heat by the walls formed by the vaporizing tubes the temperature in this combustion 20 chamber is maintained below the point of fusion of the cinders which are then easily extracted in a state of dust.

The generator forming the subject of the present specification comprises among others 25 and in combination or otherwise the following characteristics:—

(a) Each group of evaporating elements forms in itself a complete steam generator having its own functions, and provided with 30 superheating tubes and feed water heating tubes suitably connected together.

(b) All these groups of evaporating elements are arranged concentrically or in any 35 form or shape desired around a combustion chamber forming a central hearth, and in each group the vaporizing tubes are preferably forward so as to form a metallic wall for such combustion chamber and the superheating tubes and feed water heating tubes 40 are rearwards so as to surround the first while ensuring proper circulation and maximum efficiency of the gases of combustion.

(c) The ceiling of the central combustion 45 chamber is formed of steam collectors above the groups of evaporating elements and connected together; such collectors can be protected from direct action of the high temperature of the hearth by evaporating tubes of 50 small length which line their lower portion

and which at the same time increase the evaporating surface.

(d) When employing vaporizing tubes and feed water heating tubes of the double circulation type they may be provided at 55 their lower portion with flexible tubes branched upon collectors and allowing the vaporizing and feed water heating stacks to be emptied while leaving their tubes free to expand freely.

Each of the groups of evaporating elements may be formed of tubes of any types and in particular and more advantageously of removable double circulation tubes of the 60 Niclausse type.

With the arrangements adopted the distribution of the radiant heat given out by the combustion takes place progressively and 65 equally over all the surfaces forming the combustion chamber and these latter may all consequently thus produce the same quantities of steam.

As this generator is thus formed of groups of identical evaporating elements which are of relatively small size, its construction and 70 mounting is easy and it may easily be arranged to generate a very large quantity of steam.

The invention is illustrated in the accompanying drawings, in which:

Figure 1 is a plan of the apparatus having 75 three groups of evaporating elements.

Figure 2 is a vertical section on the line 2—2 of Figure 1.

Figure 3 is a vertical diagrammatic view 80 developed on the line 3—3 of Figure 1, illustrating the path for the gases.

Figure 4 is a vertical section to a larger scale of the vaporizing stack formed of one of the three groups of evaporating elements.

Figure 5 is a vertical section to the same scale of a stack of feed water heating tubes of one of the three groups of evaporating elements.

The generator is composed of three groups 85 of evaporating elements or tubular generator elements of the vertical type having removable tubes or fixed tubes while any method of circulation may be employed.

As illustrated it has been supposed that the 100

generators are of the type having tubes of the Niclausse type which can be removed upwardly or downwardly.

Each of the three steam units or generators I, II, III, comprises a vaporizing stack A, a water and steam reservoir B, a superheating stack C and a feed water heating stack D. The whole is surrounded by any suitable casing E.

10 Each vaporizing stack A is composed as shown in Figure 4 of one or more collectors a arranged horizontally or slightly inclined thereto, to which are attached removable vaporizing tubes b.

15 The collector or collectors a form a casing and are divided in a horizontal direction into two compartments by a partition c so that steam produced in each of these vaporizing tubes b passes out into the upper compartment from which it passes through a passage d and pipes e into the steam receivers B.

20 The vaporizing tubes b are supplied with water through the lower tubes b' which all lead out into the lower compartments of each of the collectors a; these lower compartments are supplied with water through tubes f which connect them to the lower portion of the water and steam receivers B.

25 In order to facilitate the separation of water and steam from collectors a an aperture g is formed in partition c to allow water carried off by the steam into the upper compartment at once to pass down into the lower compartment and from thence into the tubes b'.

30 The collectors a comprise further vaporizing tubes b'' of less length than the tubes b for protecting the lower wall of collectors a and thus to prevent deformation of such wall.

35 The assemblage of vaporizing stacks is surrounded with a partition F provided with three downwardly running apertures F' (Figure 1) through which the gases coming from the vaporizing stacks pass out. These gases are divided into two layers each of which passes through the interior of two superheaters C-C placed along partition F, then through stack D, and from thence passes into smoke pipes G communicating with a single chimney stack (not illustrated).

40 The stacks D are each formed (as shown in Figure 5) of double tubes h-h' similar to the vaporizing tubes, the said tubes h-h' leading into a collector i having a double compartment similar to the vaporizing collector.

45 Figures 2 and 3 show clearly the path of the gases, the steam and the water throughout the apparatus.

50 Pulverized fuel, solid fuel or liquid or gaseous fuel is led into the upper portion of the combustion chamber at H by any suitable means.

The cinder is removed from H' at the lower portion of the combustion chamber.

55 It has been shown above that saturated steam produced by the vaporizing stacks A passes into receivers B through pipes e e. It passes out from such receivers through tubes j into a collector tube k which feeds the six superheaters C through six tubes l.

60 Superheater's C are formed of vertical coils connected to a single collector, the said superheaters being traversed by steam in such a manner that the circulation of steam takes place in reverse direction to the circulation of the gases passing the superheaters; the steam is thus superheated progressively. The 65 superheated steam passes out from the superheaters through six pipes m uniting to a single tube n which has a cock o for taking steam from the polygenerator.

70 The feed water is returned by the feed apparatus into a collector tube p which feeds the six stacks D by six pipes q connected to the tube p as shown. When re-heated it passes out from stacks D through tubes r from thence passes into water and steam receivers 75 B after having passed through adjustable stop valves and if necessary through feed regulators.

75 Finally, in order to allow the vaporizing stacks A and stacks D to empty completely 80 while allowing the tubes of which they are composed to expand freely, their lower ends may be provided with flexible tubes s connected to two emptying collectors t, u, for the vaporizing stacks and for the stacks D respectively. It will then only be necessary to 85 open the two cocks v and w on these two collectors to empty the polygenerator completely.

90 In order to allow the vaporizing stacks A and stacks D to empty completely 95 while allowing the tubes of which they are composed to expand freely, their lower ends may be provided with flexible tubes s connected to two emptying collectors t, u, for the vaporizing stacks and for the stacks D respectively. It will then only be necessary to open the two cocks v and w on these two collectors to empty the polygenerator completely.

95 In place of utilizing the whole of the generator group, which, as illustrated, is quasi circular, a portion only may be used to form a boiler.

100 Finally, in place of providing groups of vaporizing-superheating feed water heating elements, for example, vaporizing-superheating group-elements or vaporizing feed water heating group elements may alone be provided while preserving the principle of the arrangements above described.

105 The conical shape shown is that which appears to be best, but if desired any other shape may be employed. Similarly, the tubular elements around the hearth may be combined into any shape desired, such as triangular, quadrangular, polygonal, circular.

110 What we claim is:—

115 1. In a steam generator including a com-

- bustion chamber, the combination of a plurality of units, each forming in itself a complete steam generator comprising a tubular vaporizer, a collector for the said vaporizer, a superheater and a feed water heater, the walls of the said combustion chamber being formed by the said vaporizers and the ceiling of the said combustion chamber being formed by the said collectors, means for causing the products of combustion, after passing the vaporizers, to pass to the superheaters and from thence to the feed water heaters and means for protecting the said collectors against the direct action of the heat due to combustion.
- 15 2. In a steam generator including a combustion chamber, the combination of a tubular vaporizer, a collector for the said vaporizer, said vaporizer and collector surrounding and forming respectively a portion of the 20 side walls and ceiling of said combustion chambers and means for protecting the said collector against direct action of the heat due to combustion.

In testimony whereof we have affixed our
25 signatures.

JULES NICLAUSSE.
ALBERT NICLAUSSE.
